COMPRESSED-AIR VALVE AND GAGE.

1,305,260.

Specification of Letters Patent.

Patented June 3, 1919.

Application filed May 6, 1916. Serial No. 95,838.

To all whom it may concern:

Be it known that I, LUCIEN T. EARNHEART, a citizen of the United States, and a resident of Indianapolis, county of Marion, 5 and State of Indiana, have invented a certain new and useful Compressed-Air Valve and Gage; and I do hereby declare that the following is a full, clear, and exact description thereof, reference being had to the accompanying drawings, in which like letters refer to like parts.

The object of this invention is to provide an improved air valve and a pressure gage in permanent association with the air valve 15 for introducing fluid under pressure into a pneumatic tire, tank or other receptacle.

One feature of this invention consists in providing a device with a valve, in addition to the usual valve, which additional valve is 20 positively held closed when the tire is not being charged. This absolutely prevents any escape of air from the tire and in view of the means for holding it closed, it will never leak or become ineffectual by reason of 25 wear. One difficulty with the old form of check valve in said devices has always been that it would become defective and leak. That is impossible with the extra valve which has been added in the form of device 30 shown herein.

Another feature of the invention consists in constructing said additional valve and associated parts so that it will be held closed after the means for positively holding it 35 closed has been released, by a spring which, however, will yield under high air pressure so that the high air pressure, when the air is turned in to charge the tire, will automatically open this additional valve.

Another feature of the invention consists 40 in mounting said additional valve yielding within the valve stem, the outer portion of said valve stem having an enlarged port or chamber in it and the lower portion a narrow 45 passageway which is closed at its outer end by said additional valve. The valve rod for said additional valve has a passage extending through it excepting at its inner end, said passage opening laterally before 50 it reaches the inner end of said valve rod and in the outer end of said valve member, the usual check valve is located. Hence, when air is turned in through said valve rod, 55 it will enter the chamber in the valve stem and below or inside of a piston on said valve

rod and the pressure of the air in the valve stem acting on said piston will force said valve rod and valve outwardly against the action of the spring and thus automatically open said additional valve. 60

Another feature of this invention consists in marking on said valve rod or some part associated rigidly therewith, suitable graduations for indicating the air pressure within the tire. As said air pressure increases, said 65 valve and valve rod and piston thereon, are forced outwardly farther and farther and thus said graduations are disclosed and the air pressure indicated.

Another feature of the invention consists 70 in providing a cap adapted to be screwed upon the valve stem for forcibly seating said additional valve and positively holding it closed.

The full nature of the invention will be 75 understood from the accompanying drawings and the following description and claims.

In the drawings, Figure 1 is a central longitudinal section of said device and a portion of the inner casing of a pneumatic tire. Fig. 2 is a side elevation of the device and a portion of a pneumatic tire and wheel, and a compressed air attachment at the outer end of the device. Fig. 3 is an elevation 80 of the cap used for positively seating said additional air valve. Fig. 4 is a side elevation of an automobile wheel equipped with said air valve and gage. 85

In the drawings there is shown an automobile wheel with a wooden rim S, a metal clenching rim T which may be demountable, and an outer casing U of a pneumatic tire. 90

A valve stem A extends through an inner casing P of the tire, the metal clenching rim T and the wooden rim S of the wheel. At its inner end said valve stem A is secured to the inner casing by a head within the casing and by a washer O and nut N outside the casing. 95 The valve stem is externally threaded and is secured to the rim of the wheel by a washer R and nut Q, as seen in Fig. 2. Said valve stem has a reduced air passage M through its inner portion and an enlarged air chamber B' throughout the major and outer portion thereof. Said valve stem A is not threaded throughout its entire length, but the outer portion thereof at A' is free of external threads. A dust cap V screws upon the outer end of the threaded portion of the 100 105 110

valve stem in the usual way. The outer end of the valve stem is internally threaded to receive a sleeve H and the outer end of the sleeve H is externally threaded to receive a 5 valve closing cap D which screws thereon.

The additional valve L, heretofore referred to, closes the outer end of the reduced passage M and the inner portion of the valve stem A, as seen in Fig. 1. It is the end of 10 the valve rod B which is integral with an outer enlarged portion C, the two constituting one member which will be called herein the valve member. The outer portion C of said valve rod B has an enlarged air passage in it and contains the usual check valve I. The valve rod B has a reduced air passage J through it for most of its length, but before it reaches the inner end or valve end, it divides into two laterally extending outlets K so as to discharge into the chamber B' near the inner end of the valve rod. The inner portion of said valve rod B is externally threaded to receive a piston consisting of a leather nut E, a leather cup F and a 15 small metal nut G inside of the leather cup F clamping the cup between the nuts E and G. A spring X surrounds the piston rod B and lies between the nut E and sleeve H and tends to close the valve L against low pressure, but it is weak enough to yield under 20 higher pressure and as the valve and valve rod yield, it uncovers graduations, as shown in Fig. 2, on the valve rod above the valve stem and sleeve H and thus indicates the air pressure acting on the valve, particularly 25 the back pressure from the tire while it is being charged. The numeral on the valve rod B which is nearest the sleeve H indicates the air pressure.

40 The operation is as follows:

The dust cap V is first removed and then the valve holding cap D. If there is any air pressure in the tire then, it will force the valve L and valve rod outward as far as the 45 spring X will permit, but no air can escape because of the check valve I. Then the coupling W of tube 10 from some source of compressed air is secured to the outer end of the member C, as shown in Fig. 2, and air under 50 pressure is admitted. If there is no air pressure and the valve L is seated, the incoming air under pressure will pass through the passage J in the valve rod B and issue into the chamber B' in the valve stem, between the piston E and the inner portion of the valve 55 stem and force the piston and valve rod and valve outward and thus permit the air to go through the passage M into the tire.

The air is permitted to enter the tire until 60 the pressure from the tire acting on the piston E and the valve L forces them outwardly so as to uncover the graduated part of the valve rod B, as shown in Fig. 2, and until the desired air pressure is indicated. 65 Then the supply of air is cut off and the tube

10 and nozzle W removed. The check valve I will for the time being prevent the air from escaping. The cap D is then put over the outer member C and forced inward and screwed into place on the valve stem until it 70 forces the valve L down on its seat. Therefore, said valve L will be held positively seated and closed by the cap D. Then the dust cap is put in place.

In this construction, therefore, there is no 75 chance for escape of air through the air valve after the tire has been charged and it is always provided with a gage for indicating the air pressure and an additional gage is unnecessary.

80 The invention claimed is:

1. The combination of an air valve stem having a reduced air passage through the inner part thereof and the remaining portion thereof having a chamber therein, a 85 valve member having a valve rod reciprocable in said chamber in the valve stem and provided with a needle valve on the lower end for closing the reduced passage through said valve stem, said rod having an air passage longitudinally through it for the admission of air and having laterally extending discharge passageways extending from side to side of said rod, a piston on said valve rod above said lateral discharge of the passageways through the valve rod so that the air pressure in the inner end of the chamber in the valve stem will tend to force said piston and valve rod outward and unseat the valve and admit air through the reduced passage in 90 the valve stem, and means for reseating said valve rod and positively holding the valve in its closed position.

2. The combination of an air valve stem having a reduced air passage through the 105 inner part thereof and the remaining portion thereof having a chamber therein, a valve member having a valve rod reciprocable in said chamber in the valve stem and provided with a needle valve on the lower 110 end for closing the reduced passage through said valve stem, said rod having an air passage longitudinally through it for the admission of air and a passageway extending laterally through said rod and discharging 115 into said chamber in the valve stem a distance above the needle valve at the end of the rod, a piston on said valve rod above said lateral passageways through the valve rod so that the air pressure in the inner end 120 of the chamber in the valve stem will tend to force said piston and valve rod outward and unseat the valve and admit air through the reduced passage in the valve stem, a sleeve in the upper end of said valve stem, a 125 spiral spring surrounding said valve rod and acting between the piston thereon and said sleeve for holding the valve closed against low pressure but permitting it to yield from high pressure, and a cap adapted 130

to screw on the outer end of said sleeve for forcing the valve rod inward in order to positively hold the valve seated.

3. The combination of an air valve stem 5 having a reduced air passage through the inner part thereof and the remaining portion thereof having a chamber therein, a valve member having a valve rod recipro- cable in said chamber in the valve stem and 10 provided with a needle valve on the lower end for closing the reduced passage through said valve stem and the outer end of said valve member being enlarged, a passageway through said valve stem, said passage way 15 terminating in laterally extending passage ways at a point a distance beyond the inner

end of the valve stem, a check valve in the outer end of the valve member, a sleeve in the outer end of the valve stem and surround- ing the valve rod, a piston on said valve 20 rod between said sleeve and the inner end of the air passage through the valve rod, a spiral spring on said rod between said sleeve and piston arranged to hold the valve closed against low pressure, but to yield from high 25 pressure, and means associated with the said valve structure for indicating by outward movement thereof the air pressure in the tire.

In witness whereof I have hereunto affixed 30 my signature.

LUCIEN T. EARNHEART.
